DIAL TIP FOR AUTOMATIC TELEPHONES

William J. Lustig, Springfield, Ohio

Application January 20, 1955, Serial No. 483,155

8 Claims. (Cl. 179—90)

This invention relates to dialer means for removably supporting on a dial plate of an automatic telephone a useful implement such as a pencil, pen, flashlight, and similar articles.

A primary object of the invention is to provide dialer means which is adapted to securely but removably support a useful implement on the telephone by engaging the outer face of the usual movable dial plate in and around an opening of the plate. The dialer means and the implement when the telephone dial plate is not in use are conveniently mounted and readily accessible to a person making or receiving a call.

An important object of the invention is to provide automatic telephone dialer means having a novel structural arrangement.

Another object of the invention is to provide dialer means having a structural arrangement rendering the means particularly useful for the support of implements on automatic telephone dial plates.

A particular object of the invention is to describe novel combinations of dialer means and implements.

These and other allied objects and advantages of the invention will become more apparent from the following detailed description and accompanying drawing wherein:

Figure 1 is a perspective view illustrating the use of the dialer means with an automatic telephone to support a pencil;

Figure 2 is a side elevational view of the dialer means of the structure of Figure 1;

Figure 3 is a sectional view of the dialer means of invention;

Figure 4 is a vertical sectional view of the dialer means in combination with a flashlight;

Figure 5 is an end view of the structure of Figure 4; and

Figure 6 is an elevational view partially in section of the dialer means in combination with an implement having a retractable point.

Referring to the drawings the numeral 1 indicates the indicia-carrying dial of an automatic telephone; a member 3 rotatable with respect to the dial has secured thereto a dial plate 5. The dial plate is provided with the usual finger openings 7.

Indicated at 9 is a generally cylindrical dialer means which is self-supported within an opening 7 and which dialer means supports the pencil 11.

The dialer means in its preferred embodiment is of a molded one-piece plastic construction, but may be of any other suitable material as metal or wood. For employment in conjunction with a flashlight a methylmethacrylate plastic such as Lucite or Plexiglas has been found to be most useful.

The dialer shown has a cap-like body 12 provided with a lip 13 which engages the outer face of the dial plate 5; a narrowed down extension 14 on the body tapers from the body downwardly to a face 15 which is adapted to frictionally engage the dial 1 of the telephone.

2

The extension 14 at its upper end 17 provides a dial plate-engaging portion which is adapted to pass through a finger opening 7 and to contact the plate at the opening as shown when the dialer is not in use. The taper of the extension permits the dialer device to be readily removed from one opening and to be inserted in another when a number is being dialed.

The body 12 at the end opposite the extension 14 is provided with an axial implement-receiving aperture 19, a seat for the implement being indicated at 20; the axis of the dialer which is generally cylindrical is shown by the numeral 21. As indicated in Figures 1 and 2 the implement 11 is securely supportable within the aperture of the body and the implement and dialer means are conveniently mounted on the phone for use.

It is to be particularly noted that I have provided the dialer device in such manner that the lip 13 and face 15 lie in substantially parallel planes and that these planes, when the device is mounted on the phone, extend, respectively, with the planes of the dial plate 5 and dial or dial face 1. Further the planes of the lip and face are at an angle with the axis 21 such that an implement supported on seat 20 axially is securely and conveniently positioned for use when the dialer device is mounted in the dial plate 5.

Referring now to Figure 4 there is shown therein the combination of a flashlight with the dialer device. The flashlight casing 23 is provided with a suitable snap switch 25 and a cap 26 at one end of the assembly which

30 cap may support an implement 27, for example.

The dialing means 29 at the other end of the flashlight is most suitably of a translucent material such as a methacrylate plastic to provide diffused light laterally.

35 An opening 31 in the angled face provides for an intense light from bulb 32 downwardly to facilitate inspection of the numerals of the dial face of the telephone.

The implement-receiving aperture of the body of the dialing means is provided at 33 with an internal thread; a metallic ring 35 engages the end of the dialer to protect it from wear and the ring itself engages an externally threaded sleeve 37 threaded secured in the casing 23.

40 The bulb 32 has the usual flashlight bulb contact which engages a contact of the battery 34 of the flashlight in the customary manner. A spring 38 engages between the bulb and battery retaining the same positioned; actuation of switch 25 causes the battery to engage the bulb. With the above construction the bulb 32 is removable for replacement.

50 Referring now to Figure 6 the dialing means 39 shown is formed of a somewhat flexible material such as a styrene or polyethylene; the device has a wall thickness such that it deforms under a specifically applied pressure, such as that of a thumb and most suitably the piece is substantially hollow. This permits the reception well into the device of a pen or pencil of the retractable type which is equipped with a plunger head.

55 For actuation of the plunger the dialing means 39 has molded integrally therewith an inward protuberance 41 which upon depression by a thumb contacts the plunger 43 of the implement 45 to cause actuation of the point of the implement in the usual manner. Such arrangement is particularly useful in conjunction with pencils and ball point pens and the normal operation of the dialer means is unaffected.

60 In Figure 6 the angled lip is indicated at 13' and the angled face at 15'. Preferably the implement 45 is permanently attached to the dialing means 39; for this purpose I have found that it is desirable to apply a light coating of an adhesive of uncured plastic, most suitably of the material which forms the dialer, to the end of the implement and to cure the dialer directly thereto,

I have further found that with the telephone dial plates presently in use an implement about 3" long and $\frac{1}{16}$ to $\frac{1}{2}$ inch in cross-section may be suitably supported on a dialer device having an overall width of $\frac{9}{16}$ " and a height of $1\frac{5}{32}$ ". Usually the diameter of the extension 14 at its plate-engaging portion 17 is about $1\frac{1}{32}$ " also.

Thus I have provided an arrangement which permits an implement such as a flashlight, pen or pencil, or both, to be conveniently at hand to a telephone where the same is frequently required. Of particular importance in this connection is the structure of Figure 4 for the brief notations made during a telephone call may be readily made without resort to lighting other than that provided by the flashlight.

Further, the dialing device and implement are so well supported that the telephone (Figure 1) may be tilted such that the dial and dial plate are vertical and the combination of dial device and implement will not be dislodged.

While I prefer to removably mount the implement in an aperture of the dialer I contemplate also that the implement may be molded integrally therewith if so desired; further the implement may be carried on the dialer as on the outer surface of the body portion 12.

It will be understood that this invention is susceptible to modification in order to adapt it to different usages and conditions and accordingly it is desired to comprehend such modifications within this invention as may fall within the scope of the appended claims.

I claim:

1. Means for removably supporting on a dial plate of an automatic telephone instrument at an opening thereof an implement, comprising a body adapted to engage the outer face of the dial plate around the opening thereof, and a narrowed extension of the body adapted to pass through the opening, said extension having a dial plate-engaging portion adjacent the body and being tapered downwardly from the body and the dial-plate engaging portion, and said body having implement-receiving means at the end thereof opposite the extension.

2. Means for removably supporting on a dial plate of an automatic telephone instrument at an opening to the dial thereof an implement, comprising a cap-like body having a lip adapted to engage the outer face of the dial plate around the opening thereof and a narrowed extension of the body adapted to pass through the opening, said extension having a dial plate-engaging portion adjacent the body and a dial-engaging face at its lower end, and said body having an implement-receiving aperture in the end thereof opposite the extension.

3. Means for removably supporting on a dial plate of an automatic telephone instrument at an opening thereof an implement, comprising a cap-like body having a lip adapted to engage the outer face of the dial plate around the opening thereof and a narrowed extension of the body adapted to pass through the opening, said extension having a dial plate-engaging portion adjacent the body and a dial-engaging face at its lower end lying in a plane parallel to that of said lip, and said body having an implement-receiving aperture in the end thereof opposite the extension.

4. A device which is self-supportable in a finger opening of a dial plate of an automatic telephone instrument and which itself is adapted to conveniently support an implement, comprising a body having a longitudinal axis and a transverse lip which lip is adapted to extend across

the finger opening and to engage the outer face of the dial plate, a narrowed downward extension of the body adapted to pass through the opening and to engage a portion of the plate defining the opening in a supported position of the device, the extension having a length sufficient such that the lower face thereof frictionally engages the dial in the self-supported position of the device, and the free face and lip of the body lying in parallel planes, said planes being angular to the longitudinal axis of the body, the device having implement-receiving means on the end opposite the extension.

5. Means for removably supporting on a dial plate of an automatic telephone instrument at an opening thereof a flashlight, comprising a translucent body adapted to

15 engage the outer face of the dial plate around the opening thereof, and a narrowed extension of the body adapted to pass through the opening, said extension being hollow and adapted to receive a bulb of a flashlight therein, said extension also having a dial plate-engaging portion adjacent the body, and said body having means to secure a flashlight thereto in the end thereof opposite the extension, a lower free face of said extension having an opening therethrough for the passage of light from the bulb.

20 6. Means for removably supporting on a dial plate of an automatic telephone instrument at an opening thereof a plunger type implement, comprising a cap-like body of a resilient material adapted to engage the outer face of the dial plate around the opening thereof, and

25 a narrowed extension of the body adapted to pass through the opening, said body being hollow and adapted to receive a plunger of the implement, said extension also having a dial plate-engaging portion adjacent the body at one end and an inward protuberance on the other end 30 adapted to engage with a plunger upon compression of the extension, and said body having an implement-receiving aperture in the end thereof opposite the extension.

35 7. The combination of a flashlight and a dialing device 40 for use on a dial plate of an automatic telephone, the dialing device being of a translucent material and surrounding the bulb of the flashlight and being formed to be self-supported in a finger opening of the dial plate, said device having a face engageable with the dial of the phone.

45 8. Dialer means supportable on a dial plate of an automatic telephone instrument at an opening to the dial thereof comprising a body having a lip adapted to engage the outer face of the dial plate around the opening thereof, and a narrowed extension of the body adapted to pass through the opening, said extension having a dial plate-engaging portion adjacent the body and a lower free face, the lip of the body and face of the extension being in substantially parallel planes, said body 50 having a longitudinal axis and the planes of said face and lip being disposed angularly to said axis.
